UNITED STATES PATENT OFFICE.

WILLIAM S. WELLS, OF SOUTH BETHLEHEM, PENNSYLVANIA, ASSIGNOR TO
BENJAMIN EASTWOOD COMPANY, OF PATERSON, NEW JERSEY, A COR-
PORATION OF NEW JERSEY.

LOOM.

Application filed December 9, 1919. Serial No. 343,599.

To all whom it may concern:

Be it known that I, WILLIAM S. WELLS, a citizen of the United States, residing at South Bethlehem, in the county of Lehigh 5 and State of Pennsylvania, have invented certain new and useful Improvements in Looms, of which the following is a specification.

This invention relates to looms, and it consists in certain improvements in the means 10 for impelling the shuttle whereby a considerably greater speed may be attained than is possible with looms embodying the ordinary type of shuttle impelling means, together 15 with certain other advantageous results which will be hereinafter pointed out or readily apparent to those skilled in the art.

In the accompanying drawings, two different embodiments of my invention are presented, Figures 1 to 6 illustrating one and Figures 7 to 12 the other.

Figure 1 being a front elevation;

Figure 1^a a view of a detail;

Figure 2 a side elevation;

Figure 3 a front elevation, partly in section, of certain parts appearing in Figure 1, but on a larger scale;

Figure 4 a plan of what is shown in Figure 3;

Figures 5 and 6 front and side elevations of the picker stick mounting or carrier, the picker stick and the means for attaching it (shown in section) appearing in Figure 5;

Figure 7 a side elevation of a loom embodying my invention;

Figure 8 is a section on line 8—8 in Figure 7;

Figures 9 and 10 a front elevation and a plan, on a larger scale, of certain of the 40 parts appearing in Figures 7 and 8; and

Figures 11 and 12 are views illustrating a means for automatically cutting out the shuttle impelling operation when the loom stopping means is operated.

5 The loom sides *a*, the crank shaft *b* journaled therein, the rock-shaft *c* on which the lay-swords *d* for the lay or batten *e* having the shuttle boxes *e'* are fixed, the pitmen *f* connecting the crank-shaft with the lay or batten structure (*c*, *d*, *e*) and the hand-wheels *g* for turning the crank shaft *b* manually are or may be all the same as in ordinary looms.

Referring first to the form shown in Figures 1 to 6:

In this case it will be preferable to provide a front lower rail *h* and a back frame *i* connecting the side frames *a*, and a fork shaped horizontal frame *j* connecting the rail *h* and frame *i*.

Reverse counterpart brackets each generally designated by the character *k*, and each including a sleeve *k'* and a forward up-standing arm *k*², have their sleeves fitted over and secured to the projecting ends of the shafts *c* by screws *l* (Figure 2); each bracket may also include the member *k*³ suitably secured to its underside and having a rearwardly projecting web *k*⁴ terminating in an elongated horizontal arm *k*⁵. On a stud *k*⁶ projecting from arm *k*² rearwardly of the same is fulcrumed a lever forming the carrier or mounting for the picker stick, the same being designated *m* in Figures 1 and 3 and shown in Figures 5 and 6 as including a hub *m'* journaled on stud *k*⁵, a downwardly projecting arm *m*² having a hardened plate *m*³ secured thereto and projecting downwardly therefrom to form a shoulder *m*⁴, an inwardly projecting arm *m*⁵ and an upwardly projecting arm *m*⁶; a U-shaped clip *m*⁷ receives between its branches the arm *m*⁶ and is pivoted therein on the stud *m*⁸, and above the clip there is suitably secured to arm *m*⁶ a loop *m*⁹ preferably of leather. 80 There may also be a loop stud *m*¹⁰ on the front of arm *m*⁶. The picker stick *n* is embraced by the loop *m*⁹ loosely and is received and secured by a bolt *o* in and to the clip *m*⁷, so that the stick is freely movable with the clip on its fulcrum *m*⁸ from a position of contact with arm *m*⁶ to such a limit outwardly of the arm as the loop *m*⁹ permits.

On a stud *p* in the outer end of arm *k*⁵ is fulcrumed a cocking shoe *q* having secured to its under side rear its fulcrum a plate-spring *r* which rests on the web *k*⁴ and being adapted, when the picking member *m* is swung to the position shown in Figure 1 to be depressed by the projecting plate *m*³ of 100 and then catch and hold said member in said position, or cocked, the shoe having a hardened cocking shoulder *s* to receive the contact of the shoulder *m*⁴ at that time; the upward movement of shoe *q* may be limited 105 by a set-screw *q'*. It will be understood

that the two picker-sticks *n* play in suitable slots *t* (Figure 2) in the batten *e* and that they will be equipped with pickers (not shown). The inward movement of the picking members may be limited by suitable buffers, as *u* in Figure 2 (omitted in Figure 1).

Each picking member is normally urged inwardly to the position shown in Figure 10 3, thus: A U-shaped frame *v* is secured to and rocks with the shaft *c*. Elongated springs *w* of the laminated-plate type are connected at their inner ends to studs *x* adjustable laterally in slots *y* in frame *v* and 15 at their outer ends overlie and bear upon the respective arms *m*⁵ of the picker members; between its ends each spring is upwardly opposed by an adjustable stop *z*, as a set screw, and in order to reduce somewhat 20 the downward pressure of the spring on the picking member as the latter approaches its limit on each impulse imparted thereto by the spring there is an elastic cushion 2 on the frame of the loom underlying the free or 25 outer end of the spring. The frame *j* has bearings *j'* for shaft *c*, so as to prevent the latter from being bowed by the pressure of the springs.

For cocking and tripping the picking 30 members in proper time there is the following mechanism characterized by a master lever from which both the cocking and tripping as to each picking member are effected: In suitable bearings 3 on the frame 35 *j* is journaled a rock shaft 4 equipped with a crank 5 which is connected by a pitman 6 with a crank 7 fixed on a face plate 8 secured to a shaft 9 journaled in brackets 10 on one 40 of the side frames, said shaft being connected by spiral gearing 11 with a shaft 12 journaled in the side frames and having 45 gearing 13 connecting it with the crank-shaft *b*; the gearing 11 and 13 are such that the shaft 12 makes one revolution to two of shaft *b*, so as to obtain the actuation 50 of each picking means (first one and then the other) on every other swing of the batten structure. Shaft 4 carries the aforesaid master lever 14. To the upwardly projecting 55 arm of this lever are pivoted the inner ends of two push rods 15 whose outer ends are supported by and slide in the loop studs *m*¹⁰ of the picking members and have shoulders 15' to impinge the same. The lower 60 55 arm of the lever 14 has pivotally connected thereto links 16 the outer ends of which are connected to the upwardly projecting arms of oscillators in the form of bell-crank levers 17 fulcrumed on studs 18 fixed in the inner 65 ends of the arms *k*⁵ of the brackets *k*, the outwardly projecting arms of the levers 17 overlying the inner ends of the cocking shoes *q* and having adjustable devices, as set screws 19, to bear downwardly thereagainst. 70 65 75 80 85 90 95 100 105 110 115 120 125 130

and tripping of the two picking members with respect to each other and with respect to the movements of the lay, suitable expedients for adjustment are provided; Thus the studs 20 whereby the parts 6, 15 and 16 are connected to the oscillating structure including shaft 4, crank 5 and lever 14 may be arranged in slots 21 (Figure 1) and the crank 7 may be adjustable with reference to the face-plate 6 around shaft 9 as an axis 75 (see Figure 1^a).

The structure last referred to rocks one way or the other on every back and forth movement of the batten and on each such movement through one push rod 15 (which by its shoulder 15' impinges the loop stud *m*¹⁰) it first cocks the corresponding picking member and then, through the opposite link 15 and lever 17, trips the other picking member by causing the corresponding cocking shoe *q* to be depressed against the tension of its spring. Thus the shuttle is shot back and forth across the lay, the picking member which it each time approaches being already fully pushed back for cocking by the time the shuttle reaches the picker appertaining thereto. The forward and back rocking of the batten structure (and with it the frame *v* and springs *w* and brackets *k* and the picking members and other parts carried thereby) on shaft *c* as an axis is possible with reference to the structure 4—5—14 on account of a certain amount of freedom of the parts incident to the appreciable length of the members 15, 16.

Referring, now, to the construction shown in Figures 7 to 12;

The brackets 22 secured on the ends of the rock-shaft *c* and the picking members 23 and their spring-pressed cocking shoes 24 are all substantially identical in construction and arrangement to the corresponding parts already described, excepting that the inner end of each horizontal arm 22' (corresponding to arm *k*⁵) of said bracket is eliminated 110 and an inwardly projecting arm 22'' is provided on the web 22'' thereof.

The springs 25 for urging the picking members inwardly are secured to studs 26 on brackets attached to the sides of the loom, 115 the springs projecting forwardly and having their ends arranged to pull downwardly on the arms 23' of the picking members through the medium of universal-joint connections or links 27 and having means, as set screws 28, for adjusting the pressure thereof.

The cocking and tripping of the picking members is accomplished in this case by a separate master lever 29 or oscillator for 125 each picking member, the same being fulcrumed on the frame sides *a* and having its forward end projecting between the roller 30 (on a stud 31 which projects from link 27) and the corresponding cocking shoe, there 130

65 To obtain the proper timing of the cocking

preferably being a set-screw 32 in said lever to impinge the shoe. When each lever is oscillated it will alternately cock the corresponding picking member, by impinging 5 roller 30 as it rises, and trip it, by depressing the shoe 24 as it descends.

The movements of the two levers 29 in proper time are effected from sprocket-wheels 33, which have endless chains 34 extending around them and sprocket-wheels 35 on shaft *b*, through pitmen 36 connecting eccentric points of sprocket-wheels 33 with the levers.

In connection with this form of my invention I have illustrated means for preventing tripping of the picking members and therefore cutting out their operation when the means for stopping shaft *b* and hence the loom is operated. Here 37 indicates a part of the means for stopping the loom (which means may be of any well known type), 37 here being a lever at one side of the loom, which, when thrown to the dotted position in Figure 7, to stop the loom, depresses a rod 38 which rocks a fork-lever 39 fulcrumed in the side frame, said fork-lever in turn shifting a lever 40, fulcrumed on arm 22', from between the lever 29 and the cocking shoe; lever 40 has a spring elevated button 41 for transmitting the downward pressure of lever 29 to the cocking shoe, and when said lever 40 is shifted to the dotted position (Figures 11 and 12) lever 29 will fail to depress the cocking shoe, so that the picking member remains cocked. The two levers 40 (one at each side of the loom) may be connected (Figure 11) so as both to be shifted and thus cut out both tripping members at the same time by the link 42. When the loom is turned over by hand there is a possibility of the shuttle leaving the lay and missing the box, on account of the forward movement of the lay being then too slow to keep the advancing lay against the shuttle should it tend for any reason to veer forward in its flight, and this creates an element of danger, especially since the shuttle travels at much greater velocity than in the ordinary case where it is impelled by tappet means. The advantage of cutting out the action of the picking means when the loom-stopping means is operated will therefore be apparent.

The loose picker stick is an important feature of my invention because it permits its carrier or mounting (usually forced in the act of cocking slightly beyond the cocking point) to re-act to the cocking point 60 without affecting the shuttle that has been driven into the corresponding box against the picker. The picking members and their actuating and cocking means and the means for releasing said members and re-cocking them are all formed and arranged so as to

obtain simplicity, durability and efficiency and avoid undue projection of parts.

Having thus fully described my invention, what I claim as new and desire to secure by Letters Patent is:—

1. In combination, with a supporting structure, a pair of cockable picking members movable back and forth therein and each having a spring normally urging the same in one direction and movable in the other direction to cocked position, means to hold said members in cocked position movable to release the same, and mechanism to cause release of one member from and set the other in cocked relation to said means, and vice versa, alternately, including oscillators for causing releasing movement of said means, and means to actuate the oscillators alternately.

2. In combination, with a supporting structure, a pair of cockable picking members movable back and forth therein and each having a spring normally urging the same in one direction and movable in the other direction to cocked position, means to hold said members in cocked position movable to release the same, and mechanism to cause release of one member from and set the other in cocked relation to said means, and vice versa, alternately, including oscillating levers for causing releasing movement of said means, and means to actuate the levers alternately.

3. In combination, with a frame, a rocking structure including lay-swords and a batten thereon, a shaft carrying the lay-swords, a cockable spring-pressed picking member, means to hold said member in cocked position, means also carried by said shaft to support said member and the first means, and means to alternately release said member from and re-set it in cocked relation to the first means.

4. In combination, with a frame, a cockable spring-pressed picking member, means to hold said member in cocked position, movable means including parts respectively controlling the release of said member from the first named means and resetting of said member in cocked relation to the first named means, and a batten-including forward-and-back moving structure having said member and the first-named means and both of said parts movable forward and back therewith, and moving means, supported independently of said structure, for actuating said movable means.

5. In combination, with a supporting structure, an upright spring-pressed picking member fulcrumed therein and having below its fulcrum a cocking shoulder, an upwardly impelled spring-pressed cocking shoe underlying said member and adapted to engage said shoulder and hold said member cocked, and means to alternately depress the

4
shoe to release said member and move the latter back to cocked position.

6. In combination, with a supporting structure, an upright cockable picking member fulcrumed therein and having a laterally projecting arm, a spring bearing down on said arm and normally urging said member in one direction, means on moving said member in the other direction to hold the 10 same cocked, and means to alternately release said member from and move it in said other direction into cocked relation to the first means.

7. In combination, with a supporting structure, a picker mounting fulcrumed 15 therein and normally spring held in one direction, means on moving said mounting in the other direction to hold the same cocked, means to alternately release said mounting from and move it in said other direction 20 into cocked relation to the first means, and a picking device movable in said mounting in either of said directions.

In testimony whereof I affix my signature.

WILLIAM S. WELLS.
